(57) **CLAIM**

The ornamental design for a headwrap, as shown and described.

DESCRIPTION

FIG. 1 is a perspective view of a headwrap, showing our new design;

FIG. 2 is a right-side elevational view of the invention;

FIG. 3 is a left-side elevational view of the invention;

FIG. 4 is a bottom plan view of the invention;

FIG. 5 is a top plan view of the invention;

FIG. 6 is a front elevational view of the invention;

FIG. 7 is a rear elevational view of the invention; and,

FIG. 8 is an enlarged detail view of the stitching and hatchmarks from FIG. 1.

The broken lines showing a person in FIG. 1 are environmental matter and are included for the purpose of illustrating the invention in use, forming no part of the claimed design. The broken-line circle in FIG. 8 indicates the boundary of the detail taken from FIG. 1, and forms no part of the claimed design.

The broken lines shown alongside the main vertical and horizontal seams are stitch lines and form a part of the claimed design. The cross-hatched areas of the drawings illustrate surface ornamentation.
